US00D562039S

(12) **United States Design Patent** (10) **Patent No.:** **US D562,039 S**
Browne et al. (45) **Date of Patent:** **** Feb. 19, 2008**

(54) **LAUNDRY WORKSURFACE**

(75) Inventors: **Jeffrey M. Browne**, Benton Harbor, MI (US); **Robert Fitzpatrick**, Holland, MI (US); **Seth E. Bixby**, Stevensville, MI (US)

DE 19514821 A1 11/1995
DE 19750946 A1 10/1998
FR 2510881 A 2/1983
FR 2595937 A 9/1987
GB 2164552 A 3/1986
WO 0305961 A2 5/2003

(73) Assignee: **Whirlpool Corporation**, Benton Harbor, MI (US)

Primary Examiner—Robert M. Spear
Assistant Examiner—George D Kirschbaum
(74) Attorney, Agent, or Firm—Michael D. Lafrenz; Tara M. Hartman

(**) Term: **14 Years**

(21) Appl. No.: **29/246,151**

(22) Filed: **Feb. 28, 2006**

(57) **CLAIM**

(51) **LOC (8) Cl.** **06-03**

The ornamental design for a laundry worksurface, as shown and described.

(52) **U.S. Cl.** **D6/509**

(58) **Field of Classification Search** D6/509, D6/510, 511; D19/52, 20, 75, 77, 78, 86, D19/95; D14/389; 206/562; 381/337; 108/26; 248/346.01; D3/318; 24/67.3; 281/35, 281/44, 45; D7/590
